BUILDING MATERIALS

Donald H. Sweet, Evanston, Ill., assignor to The Legan-Long Company, Chicago, Ill., a corporation of Ohio

Application June 28, 1930. Serial No. 464,527

6 Claims. (Cl. 103—7)

My invention relates to building material, and includes among its objects and advantages the fabrication of improved roofs and an improved lock shingle for use in fabricating such roofs. In 5 the accompanying drawing:

Fig. 1 is a diagram indicating how my shingle can be cut from a strip of material without waste.

Fig. 2 is a plan view of a portion of a two-thickness roof.

Fig. 3 is a plan view of a portion of a one-thickness roof.

The shingle according to the invention, in the embodiment selected for illustration, comprises 15 a quadrilateral body 10 having an upper edge 12 and a lower edge 14. The side of the shingle is defined by edge portions as follows: a vertical edge portion 16 and an inwardly extending horizontal edge portion 18, together defining a locking tab 20. There follows an upwardly and outwardly inclined edge portion 22 and a horizontal outwardly extending edge portion 24 defining a re-entrant angle 26. An inwardly and upwardly inclined portion 28 and a horizontal outwardly 20 extending edge portion 30 define a second re-entrant angle 32, vertically aligned above the first re-entrant angle 26.

Beyond the midpoint of the portion 28, the rest 30 of the side of the shingle is a geometrical replica of the lower portion, reversed by rotating the same 180° about the midpoint of the portion 28. This develops an upwardly and outwardly inclined portion 34, above which is the inwardly extending horizontal portion 36, and the vertical portion 38 reaching the upper edge 12.

In laying a two-thickness roof according to the invention, the first course 40 may be started with the usual starting strip 42, and the second course 44 is laid with its tabs 20 hooked into the angles 26 of the course below. Similarly, the succeeding courses 46, 48, 50, and 52 are each laid with their tabs 20 hooked into the angles 26 of the course below. When laid in this way, the angles 32 perform no interlocking function, being merely part of the contour of the portion of the shingle underlying the courses higher up. It will be observed that the lower edge of shingles in course 50 is substantially coincident with the upper edge of the shingle in course 40, so that no portion of the roof is covered by less than two thickness of material.

Referring to Fig. 3, the one course 54 may be started as in Fig. 2, but the next course 56 is laid 55 with its tabs hooked into the angles 32 of the course below. The third course 58 is then laid

with its tabs hooked into the angles 26 of course 56; course 60 is hooked into the angles 32 of course 58, and course 62 is hooked into the angles 26 of course 60, and so on in alternation.

It will be noted that shingles vertically above 60 each other on the roof overlap by a distance indicated at 64, which may be made the minimum necessary to prevent rain from beating through the roof at this point, so that as large a proportion as possible of the roof of Fig. 3 is covered by 66 one thickness of material only. It will also be observed that the roof of Fig. 2, and the roof of Fig. 3 may both be laid by similar operations with identical material. The zigzag lines running up and down the roof of Fig. 3 are symmetrical with each other, but in alternate vertical rows the dividing line between successive shingles comes at a different point.

Without further elaboration, the foregoing will 70 so fully explain the gist of my invention that others may, by applying knowledge current at the time of application, readily adapt the same for use under various conditions of service.

I claim:

1. A shingle having a generally quadrilateral body having the upper and lower edges parallel, and having upwardly divergent sides defined by a short vertical edge joined with a short horizontal edge providing a tab at the lower corner, then continuing in an upwardly and outwardly extending edge terminating in a second short horizontal edge extending outwardly and terminating in an upwardly and inwardly extending edge joined to a third short horizontal edge extending outwardly, the portions of the sides above and below the middle of upwardly and inwardly extending edges being reversed duplicates. 80

2. A shingle having a generally quadrilateral body having the upper and lower edges parallel, and having sides defined by a short vertical edge and a short horizontal edge extending inwardly providing a tab at the lower corner, then continuing in an upwardly and outwardly extending edge terminating in a second short horizontal edge extending outwardly and terminating in an upwardly and inwardly extending edge joined to a third short horizontal edge extending outwardly, the portions of the sides above and below the middle of the upwardly and inwardly extending edge being reversed duplicates, and the interior angles formed at the inner ends of the second and third horizontal edges being in vertical alignment. 85

3. A shingle having parallel upper and lower edges and upwardly divergent sides which are 90 complementary in reverse having tabs formed at

the lower corners and having notches above and below the middle, the lower notch being located substantially one-third of the height of the shingle from the lower edge so that the roof formed by the shingle is not less than double thickness at any place when the tabs of one course are hooked into the lower notches of the preceding course, and substantially of single thickness when the tabs of the alternate courses are hooked into the lower and upper notches respectively of the preceding courses.

4. A roof composed of uniform shingles having sides complementary one to another when reversed, the shingles having tabs on the lower corners and two vertically spaced notches in the sides, the tabs of one course being hooked into the lower notches of the preceding course, and the tabs of the next course being hooked into the upper notches of the one course.

5. A roof composed of uniform shingles having sides complementary one to another when re-

versed, the shingles having tabs on the lower corners and two vertically spaced notches in the sides, and the successive courses having their tabs hooked in alternation into the lower and upper notches of the preceding courses, the notches being spaced along the sides at about one-third and two-thirds of the height of the shingles and in vertical alignment.

6. A shingle having a generally quadrilateral body with locking tabs at two adjacent corners, and a plurality of notches in each of the side edges above the corners to receive the locking tabs of other shingles, said notches including a lower notch spaced from the tabs the proper distance to produce a two-thickness roof, and an upper notch located at such a height that the distance from the locking tab up to the lower notch plus the distance from the locking tab up to the upper notch is less than the height of the shingle by the necessary overlap for a single thickness roof.
